AUBREY HOUSTON, OF AUCKLAND, NEW ZEALAND.

FEEDING MECHANISM FOR FABRIC-MEASURING MACHINES.

Application filed May 16, 1921. Serial No. 470,218.

To all whom it may concern:

Be it known that I, AUBREY HOUSTON, a subject of the King of Great Britain and Ireland, and residing at Auckland, in the 5 Dominion of New Zealand, have invented a new and Improved Feeding Mechanism for Fabric-Measuring Machines, of which the following is a specification.

My invention relates to feeding mecha-

10 nism for fabric measuring machines and has for its primary object the provision of simple and practical mechanical means for feeding fabrics uniformly and evenly to and through fabric measuring machines.

15 Most fabric measuring machines operate through the rotation of one or more rollers by the friction produced by pulling a portion of the fabric adjacent one edge over or between the rollers, and in practice it is 20 found that the clerks often pull the fabric through by jerky uneven movements, or on other than a straight line pull so that the portion traveling over the rollers zigzags instead of remaining parallel with the edge 25 of the cloth. These methods result not only in incorrect measurement but at times crumples or tears the fabric. My invention aims to eliminate the human element in measuring fabrics and so avoid the inaccuracies and losses due to unintelligent or careless manipulation of the fabric in operating 30 the machine.

35 With the above and other objects in view, which will be readily apparent as the invention is more fully disclosed, my invention consists in combining with a measuring machine a device for intermittently feeding the fabric to and through the machine.

40 Reference is to be had to the accompanying drawings forming a part of the specification and illustrating preferred embodiments of my invention and in which similar reference numerals designate similar parts 45 throughout the several views.

In the drawings:—

Fig. 1 is a rear elevation of my invention in position adjacent a measuring machine; 50 Fig. 2 is a plan view thereof;

Fig. 3 is a vertical section taken substantially on the line 3—3 of Fig. 2;

Fig. 4 is an enlarged diagrammatical view of one of the feeding arms, showing the positions assumed by the movable roller at 55 various stages of its travel;

Fig. 4^a is an enlarged detail view of the

mounting of the rollers in one pair of arms;

Fig. 5 is an enlarged detail sectional view taken substantially on the line 5—5 of Fig. 2;

Fig. 6 is a detail view showing a modified 60 form of mounting the rollers in the traveling arms;

Figs. 7 and 8 are a section and elevation respectively of one of the rollers provided with a gripping tread, and

Fig. 9 is a rear elevation of the feeding mechanism mounted to give a longer throw to each feeding movement.

Referring now to the drawings the numeral 5 designates a fabric measuring machine of any approved type, the one herein illustrated being provided with upper and lower jaws 6 divided by a slot 7 through which the fabric is adapted to pass during the measuring operation, the fabric rotating 75 rollers carried by the jaws 6 during its passage, and the rotation of such rollers sets in motion a train of gears adapted to indicate on the dial 8 the quantity of fabric measured. The measuring machine is preferably 80 mounted on a post 9 arranged for vertical adjustment in a bracket 10 carried at the rear edge of the base plate 11 upon which my feeding mechanism is positioned. By virtue 85 of this arrangement the measuring machine and feeding mechanism may be transported to any desired location in a store or may be moved along a counter to various positions as it is desired for use. Also by mounting the measuring machine on an adjustable 90 post I am enabled to use the same feeding mechanism with various measuring machines, it being only essential that the slot 7 through which the fabric passes, is correctly located at the right height between the traveling 95 arms of the feeding mechanism.

As shown in Figs. 1 to 5 my feeding mechanism comprises a pair of traveling arms 12 pivoted upon brackets 13 carried by the base plate 11 on each side of and 100 closely adjacent to the measuring machine 5. Similar traveling arms 14 are pivoted upon the brackets 15 located in horizontal alignment with the brackets 13 but upon an upper plate 16 mounted to move on the base plate 11 toward and away from the measuring machine. Parallel slots 17 (see Fig. 2) are preferably provided in the plate 16 for guiding the movements of said plate in changing its positions, bolts 18 secured 105 in the base plate 11 extending through the slots, substantially as shown. By tighten-

ing the nuts upon the bolts 18 the plate 16 may be clamped in any adjusted position. The traveling arms 12 and 14 are connected for simultaneous movement by telescopic extension members 12^a and 14^a respectively, these members overlapping to varying degrees to adjust themselves to the changes in position of the plate 16. The arms 12 and 14 on the left side of the measuring machine are provided with lower rollers 19 (see Figs. 2 and 4), which may be mounted upon trunnions fixed in the arms and with upper rollers 20 mounted upon trunnions 21 positioned in curved slots 22 in the arms, and which are adapted to be held either in contact with the lower rollers 19 or at a distance therefrom, according to the positions occupied by the trunnions in said slots. The various positions assumed by the upper rollers 20 are diagrammatically illustrated in Fig. 4, the full line position showing the rollers separated and the trunnion 21 held at one end—hereinafter called the high end—of the curved slot 22. In this position the rollers do not grip the fabric passing between them, and upon the traveling arms being lowered, the rollers pass over the fabric to a new position before they approach each other to again grip the fabric for advancing the same during the next forward motion of the traveling arms. The positions assumed by the upper rollers as the arm 12 travels downwardly is shown in dotted lines in Fig. 4, the trunnions 21 resting upon the upper edge of the curved track 23 and being retained in the high end of the slot 22 until such slot changes its position from a substantially horizontal one to a substantially vertical one, the roller 20 then falling by gravity into the opposite end of the slot 22, which end is closer to the trunnion of the fixed roller 19. The distance between the trunnion of the fixed roller and the lower end of the slot 22 is regulated to bring the surfaces of the rollers into contact when no fabric is between them. Consequently when the fabric has been introduced between the rollers, the weight of the upper roller 20 as it approaches the lower roller, will serve to firmly grip the fabric during the upward swinging movement of the traveling arm 12. This position of the rollers will be maintained during practically the entire upward movement of the arm 12, the trunnion 21 riding upon the upper surface of the track 23 until it reaches the raised portion 24 thereof, the trunnion then riding up the incline to such raised portion and so being elevated until its surface is out of contact with the fabric, in which raised position it enters the high end of the slot 22 as shown in full lines in Fig. 4. This separation of the roller 20 from the fixed roller 19 serves to free the fabric and the rollers return to their lowermost position before

again gripping the fabric for the next advance.

The track 25 at the right of the measuring machine 5 is provided with a raised portion 26 at its lowermost extremity (see Fig. 70 1), the arrangement being such that the rollers in the arms 12 and 14 on the right of the measuring machine grip the fabric during their downward travel and release it only at the end of their downward stroke. 75 The rollers when thus separated pass over the fabric and regrip it only when the uppermost extremity of their travel is reached. The rollers in these right hand arms 12 and 14 are similar in construction to those previously described in connection with the left hand traveling arms. However, the curved slots 22^a in such arms may be positioned as desired to limit the positions of the upper rollers during the travel of the arms, as, for 80 example, shown in Fig. 4^a.

The arms 12 are connected for simultaneous movement by means of a cross-bar 27 pivoted at its opposite ends to the respective arms 12, and carrying adjacent its central portion the handle 28 whereby the feeding mechanism is operated. As best shown in Fig. 1 the arrangement is such that when the arm 12 at the left of the measuring machine is in its lowermost position the arm 12 on the right of the measuring machine is in its uppermost position or close to the measuring machine. When the handle 28 is grasped and moved to the right from its position in Fig. 1, the left hand arm 12 90 is raised and the right hand arm 12 simultaneously lowered until the positions of the arms are reversed, and the left hand arm 12 approaches close to the measuring machine. By then moving the handle 28 to the left 100 the right hand arm 12 is raised and the left hand arm lowered until they again assume the position shown in Fig. 1.

It will be clear from the above that when fabric is introduced between the rollers of the traveling arms it will be moved toward the measuring machine 5 by the left hand arms 12 and 14 and away from the measuring machine by the right hand arms 12 and 14. In operation the fabric desired to be 110 measured is first unrolled from the bolt for several yards and piled on the counter adjacent the left hand traveling arms. The edges of the fabric are then passed between the rollers 19 and 20 of the left hand traveling arms, the arm 14 being moved toward or away from the measuring machine according to the width of the fabric. The fabric is then advanced over the left hand stationary rollers 30 arranged at substantially the same 115 height as the slot 7 in the measuring machine, then through the slot 7 and over similar stationary rollers 31 adjacent the right hand end of the slot, and then between the rollers of the right hand traveling arms. As 120 125 130

the end of the fabric passes through the slot 7 it is aligned with the starting position of the measuring machine and a clamping roller or the like is released to press the fabric 5 against the operating rollers of the machine. The movement of the fabric through the slot is accordingly measured. On the first stroke of the traveling arms the end of the fabric is moved downwardly by the right hand arms 10 and when this stroke is finished the rollers 19 and 20 are automatically separated as hereinbefore described. The traveling arms are then ready to return to regrip the fabric at the uppermost end of its stroke. But, it 15 has been found that best results are obtained if the free end of the fabric is first secured adjacent the lower extremity of the right hand traveling arms. Accordingly, I preferably provide a clamp 32 (see Figs. 1 and 2) 20 which holds the end of the fabric while the arms 12 and 14 make their return stroke to grip the fabric in a new place. The advance stroke is then repeated and additional fabric pulled through the slot of the measuring machine. At the end of this stroke the rollers 25 are again automatically separated and return to regrip the fabric for the next stroke. The fabric pulled through the machine is piled loosely adjacent the right hand tracks 30 25. When the desired amount of fabric has passed through the measuring machine the portion desired is cut from the remainder of the bolt and folded as desired, the remainder being rewound upon the bolt in the usual 35 manner. Should it happen that the desired quantity of fabric has been measured when the traveling arms are intermediate the ends of their strokes, the strokes may be stopped at such intermediate positions and the fabric 40 severed. I accomplish this in the illustrated embodiment of the invention by mounting a pawl 33 upon the handle 28 (see Fig. 5) which meshes with a stationary rack 34 to lock the handle and cross-bar 27 in any desired 45 position. A spring 35 normally presses the pawl 33 into contact with the rack 34 and a hand lever 36 is pivoted on the handle so as to be grasped by the operator. When the desired measurement is effected, the operator 50 merely releases his grasp on the handle and the spring 35 throws the pawl into locking engagement with the rack.

While the quantity of fabric measured is shown on the dial 8 of the measuring machine, I also preferably provide an auxiliary dial 37 on the feeding mechanism. As shown in Fig. 2 the dial 37 is marked adjacent the rack 34 preferably so as to be easily read from above by the person operating the feeding mechanism. This dial 37 as herein shown is divided into 18 parts, preferably representing inches and when the pawl 33 is released at any intermediate position it serves to indicate on the auxiliary dial how many 55 inches of fabric has been pulled through the 60

measuring machine during that partial stroke.

While the embodiment illustrated in Figs. 1 to 5 show a travel of say 18 inches, the length of the stroke of the feeding arms 70 may be regulated as desired. For example in Fig. 9 I have illustrated an embodiment wherein the stroke of the arms 120 is materially greater than that of the embodiment shown in Figs. 1 to 5. This is accomplished 75 by pivoting the arms 120 upon the brackets 130 more remote from the measuring machine so that the arc described by the rollers of the traveling arms is materially greater. By locating the brackets 130 at the requisite 80 distance from the measuring machine and adjusting the radial lengths of the arms 120, any desired length of stroke may be obtained.

The rollers 19 and 20 may be provided 85 with any desired tread that will facilitate gripping the fabric so as to prevent slipping. One form of tread preferred by me is illustrated in Figs. 7 and 8 and comprises a multiplicity of projections 40 extending tangentially and all pointing in the same direction. Thus when a pull is put upon the projection 40 in the direction of their extension, very little opposition is made to the passage of the fabric, while if attempt is 90 made to pull the fabric in the opposite direction, each of the projections 40 then in contact with the fabric would have to be bent to permit the fabric to slide whereby great opposition is offered to the passage of 95 the fabric in such direction. This construction seems particularly desirable for firmly gripping the fabric during the advance operations of the stroke and permitting the rollers to pass over the fabric during the 100 return portion of the stroke.

I have also shown in Fig. 6 a modified form of mounting the rollers in the traveling arms when it is desired not to use the slots 22 and tracks 23. In this modification 110 I fix the trunnions 41 concentrically of the lower roller 190 and arrange the trunnion 42 eccentrically of the upper roller 200 substantially as shown. The result of such location of the rollers is that when the rollers 115 occupy the full line position shown, they will, by the weight of the upper roller, grip the fabric during any attempt to move the fabric in the direction of the arrow and will separate when attempt is made to pull fabric 120 between the rollers in the opposite direction. When, however, the upper roller is swung on its trunnion to occupy the position shown in dotted lines, just the opposite is the result and fabric passing in the direction of 125 the arrow will be allowed to freely move between the rollers while that passing in the opposite direction will be gripped. The modified form shown in Fig. 6 is particularly adaptable for returning fabric through the 130

measuring machine should it become necessary. For example, should the customer desire two yards of fabric and the clerk accidentally pull $2\frac{1}{2}$ yards through the measuring machine, the extra $\frac{1}{2}$ yard could be readily returned through the measuring machine by turning the rollers 200 on their trunnions so as to grip the fabric for the pull in the reverse direction. It is also possible to utilize the form shown in Figs. 1 to 5 for returning the fabric as above described for short distances as the rollers will grip in either direction at all portions of their stroke except after the upper roller has been moved into the high end of its slot by the inclined raised portion 24 of the track.

From the above it will be apparent that my improved feeding mechanism can be made in varied forms, all of which possess the inherent advantages of my invention and any of which will effect the desired straight line pull with the edges of the fabric maintained parallel throughout the entire movement, the fabric tautly held at the point where it passes over the measuring rollers, and the entire stroke being made uniformly and evenly so as to insure accurate measurement.

Having described my invention, I claim:—

30 1. A device for feeding fabric to and through a measuring machine, comprising arms pivoted adjacent the machine and carrying rollers adapted to releasably grip the fabric, said arms being mounted to swing toward and away from the measuring machine.

2. A device for feeding fabric to and through a measuring machine, including arms pivoted on each side of the measuring machine, said arms being mounted to swing toward and away from the measuring machine, one being arranged to advance the fabric to the machine, and the other being arranged to move it through and away from the machine.

3. A device for feeding fabric to and through a measuring machine, including arms pivoted on each side of the measuring machine, and having pairs of rollers mounted therein to grip the fabric, said arms being mounted to swing toward and away from the measuring machine, one of said arms being arranged to advance the fabric to the machine, and the other being arranged to move it through and away from the machine.

4. A device for feeding fabric to and through a measuring machine, including arms pivoted on each side of the measuring machine, and connected to move in unison throughout their entire stroke, said arms being mounted to swing toward and away from the measuring machine, one of said arms being arranged to advance the fabric to the machine, and the other being arranged

to move it through and away from the machine.

5. A device for feeding fabric to and through a measuring machine, including arms pivoted on each side of the measuring machine, and connected to move in unison, said arms being mounted to swing toward and away from the measuring machine, one being elevated toward the vertical while the other is being lowered, said arms carrying rollers arranged to grip the fabric.

6. Feeding mechanism for fabric measuring machines, comprising pairs of arms pivoted on each side of the measuring machine and carrying rollers adapted to grip the fabric adjacent its opposite edges to feed the fabric to and through the measuring machine, one arm of each pair being adjustable toward and away from the other.

7. Feeding mechanism for fabric measuring machines, comprising pairs of arms pivoted on each side of the measuring machine, and carrying rollers adapted to grip the fabric adjacent its opposite edges, to feed the fabric to and through the measuring machine, the arms adjacent one edge being adjustable toward and away from the others.

8. Feeding mechanism for fabric measuring machines, comprising pairs of arms pivoted on each side of the measuring machine, carrying rollers adapted to grip the fabric adjacent its opposite edges to feed the fabric to and through the measuring machine, and means for separating the rollers to release the fabric when desired.

9. Feeding mechanism for fabric measuring machines, comprising pairs of arms pivoted on each side of the measuring machine and carrying rollers adapted to grip the fabric adjacent its opposite edges to feed the fabric to and through the measuring machine, one of said rollers on each arm being movable toward and away from the adjacent roller.

10. Feeding mechanism for fabric measuring machines, comprising pairs of arms pivoted on each side of the measuring machine and carrying rollers adapted to grip the fabric adjacent its opposite edges to feed the fabric to and through the measuring machine, the upper roller being movable toward and away from the lower roller of each arm.

11. Feeding mechanism for fabric measuring machines, comprising pairs of arms pivoted on each side of the measuring machine, each arm carrying a pair of rollers adapted to grip the fabric adjacent its opposite edges to feed the fabric to and through the measuring machine, and stationary tracks on which the trunnions of one of said rollers is guided for moving the rollers apart and together as desired.

12. Feeding mechanism for fabric meas-

uring machines, comprising pairs of arms pivoted on each side of the measuring machine, each arm carrying a pair of rollers adapted to grip the fabric adjacent its opposite edges to feed the fabric to and through the measuring machine, and stationary cam-shaped tracks on which the trunnions of one of said rollers is guided for moving the rollers apart and together as desired.

13. Feeding mechanism for fabric measuring machines, comprising pairs of arms pivoted on each side of the measuring machine, and carrying rollers adapted to grip the fabric adjacent its opposite edges to feed the fabric to and through the measuring machine, the arms adjacent one edge being adjustable toward and away from the others, and telescoping connections between the arms on each side of the measuring machine.

14. Feeding mechanism for fabric measuring machines, comprising pairs of arms pivoted on each side of the measuring machine, each arm carrying a pair of rollers adapted to grip the fabric adjacent its opposite edges to feed the fabric to and through the measuring machine, stationary cam-shaped tracks on which the trunnions of one of said rollers is guided for moving the rollers apart and together as desired, and a clamp adjacent one of said tracks.

15. A portable feeding mechanism for fabric measuring machines, comprising a base arranged to support the measuring machine, and a pair of arms pivoted to said base on each side of the measuring machine to feed the fabric to and through the measuring machine.

40 16. A portable feeding mechanism for fabric measuring machines, comprising a base arranged to support the measuring machine, and a pair of arms pivoted to said base on each side of the measuring machine, each arm carrying a pair of rollers adapted to grip the fabric adjacent its edge to feed the fabric to and through the measuring machine, and stationary tracks mounted on said base for guiding the rollers to move them apart or together as desired.

55 17. A portable feeding mechanism for fabric measuring machines, comprising a base arranged to support the measuring machine, and a pair of arms pivoted to said base on each side of the measuring machine, each arm carrying a pair of rollers adapted to grip the fabric adjacent its edges to feed the fabric to and through the measuring machine, stationary tracks mounted on said base for guiding the rollers to move them apart or together as desired, auxiliary pivoted arms in alignment with the first mentioned arms, a plate to which said auxiliary arms are pivoted, and means for adjustably mounting said plate on said base to move

the auxiliary arms toward and from the first mentioned arms.

18. Feeding mechanism for fabric measuring machines, comprising a pair of arms pivoted on each side of the measuring machine to feed the fabric to and through the measuring machine, a pair of rollers mounted in each arm, said rollers having an anti-slipping tread to grip the fabric during the feeding movement.

75 19. Feeding mechanism for fabric measuring machines, comprising a pair of arms pivoted on each side of the measuring machine to feed the fabric to and through the measuring machine, a pair of rollers mounted in each arm, said rollers having an anti-slipping tread to grip the fabric during the feeding movement, and means to separate one roller of each pair from the other to release the fabric when desired.

80 20. Feeding mechanism for fabric measuring machines, comprising a pair of arms pivoted on each side of the measuring machine to feed the fabric to and through the measuring machine, a pair of rollers mounted in each arm, said rollers having an anti-slipping tread to grip the fabric during the feeding movement, the upper roller of each pair being adjustably mounted in said arms to permit separation of the rollers to release the fabric whenever desired.

85 21. Feeding mechanism for fabric measuring machines, comprising a pair of arms pivoted on each side of the measuring machine and carrying rollers adapted to grip the fabric adjacent its edge, means for swinging said arms simultaneously to feed the fabric to and through the measuring machine, and means for stopping said swinging movement at any point of its stroke.

100 22. Feeding mechanism for fabric measuring machines, comprising a pair of arms pivoted on each side of the measuring machine and carrying rollers adapted to grip the fabric adjacent its edge, means for swinging said arms simultaneously to feed the fabric to and through the measuring machine, and means for stopping said swinging movement at any point of its stroke, comprising a stationary rack and a ratchet moving with the swinging arms and arranged to engage the rack when released.

110 23. Feeding mechanism for fabric measuring machines, comprising a pair of arms pivoted on each side of the measuring machine and carrying rollers adapted to grip the fabric adjacent its edge, means for swinging said arms simultaneously to feed the fabric to and through the measuring machine, means for stopping said swinging movement at any point of its stroke, and indicating means arranged to show the quantity of fabric measured during an incomplete stroke.

120 24. Feeding mechanism for fabric measur-

ing machines, comprising a pair of arms pivoted on each side of the measuring machine and carrying rollers adapted to grip the fabric adjacent its edge, means for swinging said arms simultaneously to feed the fabric to and through the measuring machine, means for stopping said swinging movement at any point of its stroke, comprising a stationary rack and a ratchet mov-

ing with the swinging arms and arranged 10 to engage the rack when released, and an auxiliary indicator arranged to show the quantity of fabric measured during such incomplete stroke.

AUBREY HOUSTON.
